Design No. 444. - G. J. Zimmerman, designer to Mr. Butter. Design for a decorative stone or terracotta. Patented Nov. 6, 1887.

Fig. 1

Fig. 2

Architect, G. J. Zimmerman

Henry F. Pennington, of Rochester, N.Y. Ass't to
Henry Riddell of Cobourg, Canada.
Letters Patent No 444, Dated, Sept. 16, 1851.

The Schedule referred to in these Letter, Patent and making
part of the same.

To all whom it may concern:

Be it known that I, Elijah
F. Pennington, of the city of Rochester, in the county of
Monroe & state of New York, have invented or produced
a new & original design for ventilating stories and do
hereby declare that the following is a full & exact
description of the same.

Figure 1, represents the front.

Des 414.

of the ventilating stove, and figure 2, represents the side & back of said ventilating stove, reference being had to the accompanying drawing marked figures 1 and figure 2. —

What I claim as my Production and desire to secure by Letters Patent is the design marked figures 1 & figure 2.
